DISCHARGE GATE FOR CONCRETE
TRANSPORTATION SYSTEMS

Charles I. Longenecker, Wauwatosa, Wis., assignor to Chain Belt Company, Milwaukee, Wis., a corporation of Wisconsin

Application October 10, 1934, Serial No. 747,798

7 Claims. (Cl. 138—47)

This invention relates to discharge gates for the conduits of pressure concrete distribution systems, and has for one of its objects to provide a device of this character which will be simple in construction, comparatively inexpensive to manufacture and install, and quite efficient in actual use.

In order that the precise nature of the invention may be better understood, it may be said that in the pressure distribution of plastic concrete mixtures through closed pipe lines it is frequently desirable to discharge the mixture at various points throughout the length of the pipe line, as well as at the extreme end thereof. The lines are usually composed of steel tubing sections, each some ten feet in length, connected together by quick-detachable couplings, by means of which it is possible to readily break the line at any desired joint. However, since the tubing generally ranges from 6" to 8" in diameter, and if filled with concrete, a ten foot section thereof may weigh up to 400 to 500 pounds, such procedure is quite unwieldy, requiring the services of several men, and leaves much to be desired.

It has been previously proposed to provide a plurality of spaced discharge gates in inclined open chutes through which concrete mixtures move by gravity; and it has also been proposed to provide a plurality of discharge gates or valves in closed pipe lines for handling other materials; therefore, the present invention does not reside broadly in any such arrangement, but rather in a more or less specialized gate construction particularly adapted for closed pressure concrete transportation conduits. In its closed position, the gate provides a smooth continuation of the internal conduit surface, presenting no obstructions at which the concrete would stow under the relatively high pressures used—from 500 to 1,000 pounds per square inch; and when opened, which may be easily accomplished by one man, it may be readily maintained in a position in which it will in no wise interfere with the forms, or with a distributing chute which may be located to receive the mixture from the discharge opening, as in my prior co-pending application filed May 18, 1934, Ser. No. 726,392, entitled Distributing mechanism for pressure concrete transportation systems. The gate is furthermore so constructed and arranged that when closed it is substantially leak-proof at the above mentioned pressures, and in actual field use it has been found quite efficient for its intended purpose.

With the above and other objects in view, which will appear as the description proceeds, the in-

vention consists in the novel details of construction, and combinations and arrangements of parts, more fully hereinafter disclosed, and particularly pointed out in the appended claims.

Referring to the accompanying drawings, in which like reference characters designate like parts in all the views:—

Figure 1 is a side elevational view of one section of a concrete transportation pipe line, with a discharge gate structure in accordance with the present invention in place thereon, the gate being shown in its closed position;

Figure 2 is a similar view, showing the gate in the open position it may occupy if no distributing chute or trough is being used;

Figure 3 is a similar view, partly broken away, illustrating the open position in which the gate may be held when a distributing chute is to be used, as in my said co-pending application;

Figure 4 is a fragmentary end elevational view, on a somewhat enlarged scale, of portions of the operating levers and links, as seen from the left of Figure 1;

Figure 5 is an enlarged longitudinal vertical sectional view through the gate structure shown in Figure 1;

Figure 6 is a horizontal sectional view, taken approximately on the plane indicated by the line 6—6 of Figure 5, looking down; and

Figures 7 and 8 are transverse sectional views, taken approximately on the planes indicated respectively by the lines 7—7 and 8—8 of Figure 5, looking in the direction of the arrows.

Referring to the said drawings, 10 indicates a length of steel tubing or other similar conduit which is provided substantially mid-way between its ends with an elongated aperture 11. The said tubing is provided at its ends with the elements 12 and 13 of a quick-detachable coupling here shown as being of the type described and claimed in the co-pending application of Charles F. Ball, filed May 26, 1933, Ser. No. 673,059, entitled Pipe couplings. These elements are slipped on to the pipe ends and welded or otherwise rigidly secured thereto, and before this operation is performed a frame member 14 constituting one element of the present invention is slipped upon the pipe section and welded thereto as indicated at 15 in cooperative relationship to the opening 11 substantially shown in Figures 1, 2, 3 and 5.

The said frame member 14 as clearly shown, is substantially semi-cylindrical in shape and is provided at its ends with the completely circumferential ring members 16 which encircle the pipe 10. The said ring members 16 are spaced

somewhat further apart than the length of the aperture 11, so that portions 17 of the pipe section project inwardly beyond the said ring members 16 and form sealing seats adapted to co-operate with the closure member, as will appear more fully below.

The said closure member 18 is likewise substantially semi-cylindrical in form and is of such length as to be received between the encircling ring portions 16 of the frame member 14, as shown in Figure 1. The closure member is provided with a pair of longitudinally extending arms 19 which have formed in their extremities elongated slots 20 for the reception of a pin or shaft 21, which is mounted in a tubular sleeve 22, welded or otherwise rigidly secured to spaced ears 23, which in turn are welded to the pipe section 10, as will be clear from Figures 1 and 8.

The frame member 14 is provided with the upstanding transversely spaced ears 25, in which is mounted a pin or shaft 26, carrying the lower ends of the spaced operating levers 27 which levers are rigidly connected together at their outer extremities by a transversely extending handle member 28 which is welded or otherwise rigidly secured thereto. The said levers 27 may also have an intermediate transverse brace member 29 secured to them, as clearly shown in Figures 1 and 4.

The closure member 18 has a transverse pin or shaft 30 secured to it, which shaft mounts the lower ends of the transversely spaced links 31, the upper ends of which are pivotally connected by means of the pin or shaft 32 to the operating levers 27, as clearly shown in Figures 1 to 4 of the drawings.

The longitudinal edges of the closure member 18 are recessed as at 35 to receive a substantially rectangular packing means 36 of rubber or other suitable material which may be retained in place by longitudinal metal strips 37 embedded within the member 36 in the course of manufacture and which strips have secured to them threaded studs 38 adapted to pass through suitable apertures 39 in the member 18 and receive nuts 40 all as is clearly shown in Figure 7. The longitudinal members of the packing means 36 are adapted to engage with the longitudinal edges of the semi-cylindrical frame member 14, as illustrated in Figures 5 and 7, while the end members 41 of the said packing means 36 follow the semi-cylindrical contour of the closure member 18 and are adapted to engage the sealing seat portions 17 of pipe section 10, as clearly shown in the said figures. There is thus provided an effective packing or seal which completely surrounds the opening 11 when the closure member 18 is in closing position, as shown in Figures 5, 6 and 7, which will effectively prevent leakage of the more liquid portions of the concrete mixture, even under the relatively high pressures which are commonly employed in systems of this type.

The closed position of the gate structure is illustrated in Figures 1, 5, 6 and 7, wherein the operating levers 27 are substantially vertical with the links 31 in alignment therewith, whereby the closure member 18 may be retained in its uppermost position substantially as illustrated. In this position the said closure member constitutes a substantially smooth continuation of the inner surface of the conduit 10, and presents no obstructions which might interfere with the flow of the concrete mixture to such an extent as to

produce stowing thereof with its attendant difficulties.

When it is desired to discharge concrete through the opening 11, the handle 28 is grasped and the operating levers 27 swung in a clockwise direction, as viewed in Figure 1, to the position shown in Figure 2. This movement through the linkage 31 will swing the closure member 18 about the pivot pin 21 to a substantially vertical position, as shown in said Figure 2, whereby the concrete mixture flowing through the tube 10 may be discharged by the action of gravity through the aperture 11.

The position shown in Figure 2 is that which may be assumed by the parts if a distributing chute is not being employed. However, if such a chute is being used in the manner disclosed in my said prior application No. 726,392, the present gate structure may be caused to occupy the positions illustrated in Figure 3. That is to say from the position shown in Figure 2 the operating levers 27 may be moved upwardly somewhat, such movement through links 31 drawing the closure member 18 to a position closely adjacent the conduit 10, so that the said closure member will not interfere with the distributing chute 50, as will be readily understood from Figure 3. The parts may be retained in this position by means of a suitable prop member 51 which is pivotally mounted upon the transverse pin 32 and which 30 may be swung from an inoperative position wherein it is in engagement with the transverse brace member 29, as shown in Figures 1, 2 and 4, to an operative position, as shown in Figure 3, wherein its lower notched end engages with the upper surface of the pipe 10 and serves to retain the operating levers 27, links 31 and closure member 18 in the positions shown therein.

While one form of the invention has been illustrated and described, it is obvious that those skilled in the art may vary the precise details of construction and arrangement of parts without departing from the spirit of the invention, and therefore it is not wished to be limited to the above disclosure except as may be required by the claims.

What is claimed is:

1. In a discharge gate structure for the closed conduits of pressure concrete distribution systems, a frame member arranged to be secured to said conduit at an opening therein; a gate member arranged to be moved to and from a co-operative position with said frame member, wherein it closes said opening and provides a smooth continuation of said conduit; means providing a pressure tight joint around said opening between said members when in co-operating position; and means for moving said gate member.

2. In a discharge gate structure for the closed conduits of pressure concrete distribution systems, a frame member arranged to be secured to said conduit at an opening therein and to span the same; a pivoted gate member arranged to be swung to and from a co-operative position with said frame member, wherein it closes said opening and provides a smooth continuation of said conduit; sealing means carried by said gate member, arranged to engage with said frame member and with portions of said conduit when the members are in co-operative relation, to provide a pressure tight joint completely surrounding said opening; and means for swinging said gate member.

3. In a discharge gate structure for the closed

conduits of pressure concrete distribution systems, a substantially semi-cylindrical frame member having circumferential end portions, arranged to be secured to the conduit at an opening therein, with portions of said conduit adjacent the opening projecting inwardly beyond said circumferential end portions to constitute sealing seats; a substantially semi-cylindrical gate member arranged to be moved to and from a co- operative position with said frame member between the said circumferential end portions thereof, said gate member in such position providing a smooth continuation of said conduit; sealing means carried by said gate member, having portions arranged to engage the longitudinal edge portions of said frame member, and curved end portions arranged to engage with said sealing seat portions of said conduit, whereby there is provided a pressure tight joint completely surrounding said opening; and means for moving said gate member to and from said closing position, and positively maintaining it therein.

4. In discharge gate structure for the pressure conduit of a plastic concrete transportation system, said conduit having a discharge opening, a pivoted gate member for closing said opening; an operating lever pivoted on said conduit; links pivotally connected to said gate member and to said lever, whereby upon movement of the latter said gate member may be moved from its closing position to an open position adjacent said conduit in which it will not interfere with concrete receiving means positioned below said opening; and means comprising a prop member carried by said operating lever and engageable with said conduit, for retaining said gate in said open position.

5. In discharge gate structure for the pressure conduit of a plastic concrete transportation system, said conduit having a discharge opening, a pivoted gate member for closing said opening; a pivoted operating lever; and links connected to said lever and gate member, said lever and links being arranged through movement of said lever in one direction to a predetermined limit to swing said gate to an open position substantially per-

pendicular to the axis of said conduit, and upon partial reverse movement of said lever to continue said opening movement of the gate member until the latter occupies a position approximately parallel to said conduit and removed from said opening.

6. In discharge gate structure for the pressure conduit of a plastic concrete transportation system, said conduit having a discharge opening, a pivoted gate member for closing said opening; a pivoted operating lever; links connected to said lever and gate member, said lever and links being arranged through movement of said lever in one direction to a predetermined limit to swing said gate to an open position substantially perpendicular to the axis of said conduit, and upon partial reverse movement of said lever to continue said opening movement of the gate member until the latter occupies a position approximately parallel to said conduit and removed from said opening; and means for positively retaining said gate in said approximately parallel position.

7. In discharge gate structure for the pressure conduit of a plastic concrete transportation system, said conduit having a discharge opening, a pivoted gate member for closing said opening; an operating lever pivoted on said conduit, movable from a position substantially perpendicular to said conduit, to a position parallel to and engaging with said conduit; links connected to said lever and gate member, said lever and links being arranged through movement of the lever from said perpendicular to said parallel position to swing said gate member to an open position substantially perpendicular to said conduit and clear of said opening, and upon partial reverse movement of the lever to continue the opening movement of the gate member until the latter occupies a position approximately parallel to said conduit and removed from said opening; and a prop member arranged to positively maintain said gate in said last named position.

CHARLES I. LONGENECKER. 45
